US00D688563S

(12) **United States Design Patent**
Cohen et al.

(10) **Patent No.:** **US D688,563 S**
(45) **Date of Patent:** **** Aug. 27, 2013**

(54) **CONTAINER SHROUD**

- (71) Applicants: **Erica Eden Cohen**, New York, NY (US); **Nathaniel Giraitis**, New York, NY (US); **William F. Gordon**, Chicago, IL (US); **Kevin Harrity**, Oak Creek, WI (US); **Jonathan N. Mandell**, Gurnee, IL (US); **Nicholas Oxley**, New York, NY (US); **Jacob Palmborg**, Brooklyn, NY (US); **Jessi Pervola**, Brooklyn, NY (US); **Richard Whitehall**, New York, NY (US)
- (72) Inventors: **Erica Eden Cohen**, New York, NY (US); **Nathaniel Giraitis**, New York, NY (US); **William F. Gordon**, Chicago, IL (US); **Kevin Harrity**, Oak Creek, WI (US); **Jonathan N. Mandell**, Gurnee, IL (US); **Nicholas Oxley**, New York, NY (US); **Jacob Palmborg**, Brooklyn, NY (US); **Jessi Pervola**, Brooklyn, NY (US); **Richard Whitehall**, New York, NY (US)

- (73) Assignee: **S.C. Johnson & Son, Inc.**, Racine, WI (US)

(**) Term: **14 Years**

(21) Appl. No.: **29/451,318**

(22) Filed: **Mar. 30, 2013**

Related U.S. Application Data

- (62) Division of application No. 29/436,708, filed on Nov. 8, 2012, now Pat. No. Des. 682,095, which is a division of application No. 29/386,808, filed on Mar. 4, 2011, now Pat. No. Des. 673,448.

(57) **CLAIM**

The ornamental design for a container shroud, as shown and described.

DESCRIPTION

FIG. 1 is an isometric view of a top, front, and right side of the container shroud showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines are included for the purpose of illustrating the portions of the container shroud that form no part of the claimed design.

1 Claim, 4 Drawing Sheets
